UNITED STATES PATENT OFFICE.

ALBERT H. TAYLOR, OF EASTON, PENNSYLVANIA, ASSIGNOR TO INGERSOLL-RAND COMPANY, OF JERSEY CITY, NEW JERSEY, A CORPORATION OF NEW JERSEY.

THROTTLE-VALVE MECHANISM FOR AUTOMATIC-ROTATION HAMMER-DRILLS.

1,127,110.

Specification of Letter's Patent.

Patented Feb. 2, 1915.

Application filed July 15, 1913. Serial No. 779,099.

To all whom it may concern:

Be it known that I, ALBERT H. TAYLOR, a citizen of the United States, residing at Easton, in the county of Northampton and 5 State of Pennsylvania, have invented a certain new and useful Improvement in Throttle-Valve Mechanism for Automatic-Rotation Hammer-Drills, of which the following is a specification.

10 This invention relates to fluid operated hammer drills having an independent motor for rotating the steel and more particularly to valve mechanism for controlling the fluid supply to the hammer cylinder and the rotating motor. In drills of this type as previously used, a simple throttle valve has controlled the fluid supply into both the hammer cylinder and the rotating motor. For 15 this reason the hammer piston and the rotation have always operated simultaneously and could not be independently controlled.

The object of this invention is to provide a valve mechanism so arranged that the hammer piston and the rotating motor can 20 be operated, each separately or both at the same time, and also to provide for a variable fluid supply to the hammer cylinder during the full operation of the rotating motor.

A further object is to provide a valve 25 which cuts off the oil supply from the fluid admission chamber during the non-operation of the drill so that leakage of the oil is avoided and the oil supply can be renewed without disconnecting the fluid supply line.

30 With these objects in view, I have devised a valve mechanism, a practical embodiment of which is shown in the accompanying drawings in which—

Figure 1 is a side elevation of the drill 35 showing the various positions of the valve handle. Fig. 2 is a longitudinal section through the drill on the line II—II of Fig. 1. Fig. 3 is a transverse section through the valve and oil chamber on the line III—III

40 of Fig. 2. Fig. 4 is a transverse section through the rotating mechanism on the line IV—IV of Fig. 2. Figs. 5 and 6, 7 and 8, 9 and 10, 11 and 12 are sections through the throttle valve on lines A—A and B—B of

45 Fig. 3 showing the position of the valve ports in the first operating position, non-operating position, and second and third operating position, respectively.

The drill, as shown, comprises a cylinder 50 1 in which reciprocates a piston 2 which

strikes on the anvil block 3 resting against drill steel 4. The drill steel 4 is rotated through the sleeve 5 by an independent motor 6, here shown of the type described in my previous Patent #998,932, July 25th, 60 1911, but which may be of any type which rotates the steel independently of the hammer piston action. From the valve chest 7 of this rotating motor, a fluid inlet passage 8 leads to a valve port 9 which opens into 65 one side of a slightly conical valve bore 10 in the head block 11. Rotatably mounted in the valve bore 10 is a throttle valve 12 which is provided with a stem 13 on the outer end of which is secured a throttle handle 14. 70 In the opposite face of the valve bore 10 is a cylinder supply port 15 which leads by a passage 16 to the distributing valve 17 which operates the hammer piston 2 and which may be of any ordinary construction. 75 The interior of the valve plug 12, as shown, is hollow forming with the adjacent portion of the valve bore 10 a supply chamber 18 to which fluid is supplied from the fluid supply (not shown) through an inlet opening 19. 80 Through the valve plug 12 and adapted to supply fluid from the supply chamber 18 to the ports 9 and 15 are admission ports 20 and 21. The port 20 which normally controls the passage of fluid to the port 9 covers 85 a considerably greater arc than port 21.

In the head block 11 is an oil chamber 22 adapted to be filled from the outside by the removal of screw plug 23. From this oil chamber an oil passage 24 leads to an interior surface of the valve bore 10. In the valve plug 12 is a port 25 which registers with the opening of the passage 24 to allow oil from the chamber 22 to be drawn into the supply chamber 18. The arrangement 90 of ports in the valve bore and in the valve plug allows the valve plug to be placed in four major positions, one non-operating position and three operating positions.

The first operating position is shown in 95 Figs. 5 and 6. This position of the valve 12 corresponds to the position of the valve handle indicated as 14^A on Fig. 1. The large port 20, which normally controls the port 9 is thrown around so far as the register to a slight extent with the port 15 which communicates with the hammer cylinder while the ports 9 and 21 are closed. In this position of the valve, the oil passage 24 is closed.

In the position shown in Figs. 7 and 8, 110

which is the non-operating position, corresponding to the position of the handle shown in solid lines in Fig. 1, no fluid is admitted to the hammer cylinder or the rotating motor and the oil passage 24 is also closed.

In the second operating position shown in Figs. 9 and 10 and which is intermediate of the non-operating position and the third operating position, the valve handle being in the position indicated as 14^B on Fig. 1, one extremity of the port 20 will register with the port 9 while the ports 15 and 21 will be out of register, fluid in this position being admitted only to the rotating motor. In this position of the valve the ports 25 and 24 will register allowing oil to be drawn from the oil chamber 22.

In the third operating position shown in Figs. 11 and 12 and which corresponds to the position of the handle 14, indicated on Fig. 1 as 4^C, the valve is in such a position that the port 20 registers with the port 9 while the port 21 is fully opened to the port 15, pressure being thus admitted to both the rotating motor and the hammer cylinder. In this position the port 24 registers with the port 25 and oil is admitted to the supply chamber 18.

In operation, to start the hole the drill operator throws the valve handle to the first operating position thus admitting fluid pressure through the ports 20 and 15 into the drill alone so that the hammer piston strikes on the steel but the steel does not rotate. Under these conditions, a hole can be started easier than if the rotation was operating and the steel turning, since when turning it has a tendency to move about on the surface of the rock. After the hole is started the valve is thrown into the third operating position, by throwing the valve handle into the position 14^C. This is the normal operating position for ordinary work, both drill cylinder and rotation having a full supply of fluid. When drilling through soft ground or through seams a powerful rotation and a slight piston blow are desirable. Any degree of piston blow with full rotation can be obtained by moving the valve handle to positions intermediate of the second and third operating positions so that ports 21 and 15 only partly register and the flow of operative fluid to the hammer cylinder is partly throttled.

In removing a steel from a hole it is often advantageous to have the steel rotate without any reciprocation of the hammer piston. This condition can be obtained by placing the valve in the second operating position with the valve handle in the position 12^B.

By having the oil supply from the oil chamber cut off when the valve is in the non-operating position, waste of the oil is

prevented and it is possible to fill the oil chamber without disconnecting the pressure line from the drill, as heretofore.

It is to be understood that the present showing and description discloses only one specified modification of my invention and other forms and modifications are included in the spirit and scope of the invention as expressed in the claims.

What I claim is:

1. In a fluid operated hammer drill, having a cylinder and piston, a drill steel, and an independent motor for rotating said drill steel, a fluid inlet and a throttle valve arranged to supply fluid from said inlet only to said cylinder in one position, and only to said rotating motor in another position.

2. In a fluid operated hammer drill, having a cylinder and piston, a drill steel and an independent motor for rotating said drill steel, a fluid inlet and a throttle valve arranged to supply fluid from said inlet only to said cylinder in one operating position and only to said rotating motor in another operating position, and to cut off supply from both hammer cylinder and rotating motor in a non-operating position.

3. In a fluid operated hammer drill, having a cylinder and piston, a drill steel, and an independent motor for rotating said drill steel, a fluid inlet and a throttle valve arranged to supply fluid from said inlet only to said cylinder in one operating position and only to said motor in another operating position and to cut off the fluid supply from both the hammer cylinder and the rotating motor in a non-operating position intermediate of said operating positions.

4. In a fluid operated hammer drill, having a cylinder and piston, a drill steel and an independent motor for rotating said drill steel, a fluid inlet and a throttle valve arranged to supply fluid from said inlet only to said cylinder in one position, only to said rotating motor in another position, and to both hammer cylinder and rotating motor in a third position.

5. In a fluid operated hammer drill, having a cylinder and piston, a drill steel, and an independent motor for rotating said drill steel, a fluid inlet and a throttle valve arranged to supply fluid from said inlet only to said cylinder in one operating position, only to said rotating motor in another operating position, to both hammer cylinder and rotating motor in a third operating position, and to cut off the fluid supply to both hammer cylinder and rotating motor in a non-operating position.

6. In a fluid operated hammer drill, having a cylinder and piston, a drill steel and an independent motor for rotating said drill steel, a fluid inlet throttle valve arranged to supply fluid from said inlet only to said cylinder in one operating position, only to

said rotating motor in another operating position, to both said cylinder and said rotating motor in a third operating position, and to shut off the supply from both hammer cylinder and rotating motor in a non-operating position intermediate of said first and second operating positions.

7. In a fluid operated hammer drill, having a cylinder and piston, a drill steel, and an independent motor for rotating said drill steel, a fluid inlet and a throttle valve arranged to supply fluid from said inlet only to said hammer cylinder in one position, only to said rotating motor in another position, and to both said hammer cylinder and said rotating motor in a third position, intermediate positions between the second and third positions giving full supply to said rotating motor and variable supply to said hammer cylinder.

8. In a fluid operated hammer drill, having a cylinder and piston, a drill steel, and an independent motor for rotating said drill steel, a fluid inlet and a throttle valve arranged to supply fluid from said inlet only to said hammer cylinder in one operating position, only to said rotating motor in another operating position, to both said hammer cylinder and said rotating motor in a third operating position, to shut off supply to both hammer cylinder and rotating motor in a non-operating position, and to give full supply to said rotating motor and a variable supply to said hammer cylinder in positions intermediate of said second and third operating positions.

9. In a fluid operated hammer drill, having a cylinder and piston, a drill steel, and an independent motor for rotating said drill steel, a fluid inlet and a throttle valve arranged to supply fluid from said inlet only to said hammer cylinder in one operating position, only to said rotating motor in another operating position, to both said hammer cylinder and said rotating motor in a

third operating position, to give a full supply to said rotating motor and variable supply to said hammer cylinder in positions intermediate of said second and third operating positions, and to shut off supply to both hammer cylinder and rotating motor in a non-operating position intermediate of said first and second operating positions.

10. In a fluid operated hammer drill, having a cylinder and piston, a drill steel and an independent motor for rotating said drill steel, a fluid inlet, and a throttle valve having ports arranged to supply fluid from said inlet only to said hammer cylinder in one position and to both said hammer cylinder and said rotating motor in another position.

11. In a fluid operated hammer drill having a hammer cylinder and piston, a drill steel and an independent motor for rotating said drill steel, a fluid inlet, an oil chamber and a throttle valve arranged to supply fluid from said inlet to operate said hammer cylinder and said rotating motor separately or simultaneously and having a port to admit oil to said fluid inlet from said oil chamber only during such operation.

12. In a fluid operated hammer drill having a hammer cylinder and piston, a drill steel and an independent motor for operating said drill steel, a fluid inlet, an oil chamber and a throttle valve arranged to admit fluid to operate said hammer piston and said rotating motor, and having a port arranged to admit oil to said hammer piston and rotating motor only during the operation thereof.

In testimony whereof, I have hereunto set my hand.

ALBERT H. TAYLOR.
